CLAIM

(57) The ornamental design for a smart card reader, as shown and described.

DESCRIPTION

FIG. 1 is a top, front and right side perspective view of smart card reader, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a top, rear and right side perspective view thereof; and,

FIG. 9 is a top, rear and right perspective view in an expanded configuration.

The broken lines shown in the figures depict portions of the smart card reader that form no part of the claimed design.
